CLAIM

The ornamental design for an insect habitat stacker, as shown and described.

DESCRIPTION

FIG. 1 is a front perspective view of an insect habitat stacker showing the new design;

FIG. 2 is a side elevation view thereof;

FIG. 3 is another side elevation view thereof;

FIG. 4 is a front elevation view thereof;

FIG. 5 is a back elevation view thereof;

FIG. 6 is a top plan view thereof; and,

FIG. 7 is a bottom plan view thereof.

The broken lines shown in the drawings depict portions of the insect habitat stacker that form no part of the claimed design.
